CLAIM

The ornamental design for a cutting tool, substantially as shown and described.

DESCRIPTION

FIG. 1 is a front perspective view of a cutting tool showing my new design;

FIG. 2 is a top plan view thereof;

FIG. 3 is a front elevational view thereof, the rear elevational view being a mirror image thereof;

FIG. 4 is an end elevational view thereof, the other end being a mirror view thereof; and

FIG. 5 is a bottom plan view thereof.
